UNITED STATES PATENT OFFICE.

FRANK JOSEPH BISCHOF, OF DETROIT, MICHIGAN.

CURTAIN-POLE.

Specification of Letters Patent.

Patented Apr. 2, 1918.

1,261,685.

Application filed August 29, 1917. Serial No. 188,768.

To all whom it may concern:

Be it known that I, FRANK J. BISCHOF, a citizen of the United States, and a resident of the city of Detroit, county of Wayne, and State of Michigan, United States of America, have invented a new and Improved Curtain-Pole, of which the following is full, clear, and exact description.

My invention has for its object to provide a curtain pole having a guide with a slot in its bottom, a hanger extending upwardly in the slot and provided with rollers rotatably mounted at its sides for engaging the guide at the sides of the slot. The guide is preferably mounted in a casing, having a slot through which the hanger extends.

Another object of the invention is to provide a hanger with eyes through which an operating cord extends, the eyes being spaced apart and a wedge being disposed under the cord between the eyes to secure the cord to the hanger at the eyes. This wedge is mounted on a plate which is slideable in guides on the hanger and which is held in place by means provided.

Other objects of the invention will appear in the following specification, in which the preferred form of my invention is described.

In the drawings similar reference characters refer to similar numbers in all the views, in which—

Fig. 1 is a longitudinal sectional view showing my curtain pole;

Fig. 2 is an inverted sectional plan view of Fig. 1;

Fig. 3 is an enlarged sectional view on the line 3—3 of Fig. 1;

Fig. 4 is an enlarged sectional view on the line 4—4 of Fig. 1;

Fig. 5 is a view showing one of the hangers in elevation;

Fig. 6 is a sectional view on the line 6—6 of Fig. 5;

Fig. 7 is a perspective view illustrating the plate having the wedge which is used in connection with the hanger;

Fig. 8 is a view illustrating the key which is used to operate the spring tongue of the plate; and

Fig. 9 is a sectional view of the line 9—9 of Fig. 5.

By referring to the drawings it will be seen that a guide 10 is provided having an inverted U-shaped portion 11 at its top and a slot 12 at its bottom. The guide 10 is disposed in a casing 13 which has an in-

verted U-shaped portion 14 at its top in which the U-shaped portion 11 of the guide is disposed, the casing 13 also having a slot 15 in its bottom. An inverted U-shaped support 16 is disposed with its sides at the outer sides of the U-shaped portion 14 of the casing 13 and in the said U-shaped portions 11, 14 and 16 there are registering orifices in which a pin 17 is disposed, the said pin 17 serving not only to hold the casing 13 to the support 16, but it also serves to hold the guide 10 in position in the casing 13. Extending through the slots 15 and 12 there are hangers 18 and 18^a, each of the said hangers 18 and 18^a having a bearing 19 in which a stud 20 is journaled, rollers 21 being mounted on the stud 20 at the sides of the hangers, the said rollers 21 engaging the guide 10 at the sides of the slot 12 therein. It will be seen that with this construction the hangers may move from one end of the guide to the other and that the rollers 21 will assist in this movement while preventing the hangers from passing through the slot 12. The hangers 18 and 18^a extend up through the guide 10 to its U-shaped portion 11.

Means are provided for securing an operating cord 22 to the hangers 18 which I will now describe. Each of the hangers 18 is provided with two eyes 23 which are spaced apart, the said hangers also being provided with guides 24 in which a plate 25 is slidably disposed, this plate 25 being provided with a wedge 26 which is disposed under the operating cord 22 between the eyes 23 so that when the plate 25 is moved upwardly it will force the wedge 26 upwardly and thereby press the operating cord 22 against the sides of the upper portions of the eyes 23 to secure the operating cord 22 to the hangers 18. As a means of holding the plate 25 in position when it has been moved upwardly, as has been stated, I provide the plate 25 with a spring tongue 27 the end of which is adapted to engage the hanger 18 at the bottom of an opening 28 therein. It will therefore be seen that when the plate 25 has been moved upwardly and the edge 26 presses against the operating cord 22 between the eyes 23 to secure the operating cord relatively to the hanger, that the bottom of the spring tongue 27 will engage the hanger 18 at the bottom of the opening 28 therein to prevent a downward movement of the plate 25 until the spring 27

is pressed out of the opening 28 in the hanger.

As a means of pressing the spring tongue 27 out of the opening 28 I provide a key

- 5 29 having a pin 30 at its end, which fits an orifice 31 in the plate 25. The key 29 may be employed as illustrated in the dotted lines in Fig. 6 of the drawings, and with this pin 30 inserted in the orifice, it may 10 be used to press the spring 27 free from the opening 28 so that the plate 25 may be pressed downwardly, it being possible to press the said plate 25 downwardly by means of the key 29 after the spring tongue 27 has been moved free from the opening 28, for the pin 30 which is in the orifice 31 will enable the operator to conveniently 15 press the plate 25 downwardly after he has removed the spring tongue 27 from the opening 28.

The operating cord 22 is disposed around a pulley 37 at one end of the casing 13, a guard member 34 being provided to prevent the operating cord 22 from slipping off of 25 the pulley 23. The pulley 37 and the guard member 34 are held in place by a bolt 33, the said bolt 33 also extending through an opening in a block 35, which is disposed between the pulley 37 and the guide 10. The bolt 33 extends upwardly through the slot 12 and engages the guard member 34 in the guide 10. A U-shaped member 32 being inserted through an opening 36 in the bottom of the guide 10 and having one of its 30 arms disposed above the bottom of the guide 10 and below the guard member 34, the other arm of the U-shaped member 32 being disposed below the bottom of the guide 10 and above the block 35.

- 35 40 As has been stated, the bolt 33 which serves as a bearing for the pulley 37, is disposed through the block 35 and through an opening in the guard member 34. The bolt 35 is also disposed through openings in the 45 arms of the U-shaped member 32. The operating cord 22 is secured to one of the hangers 18 at one side of the pulley 37, the operating cord 22 being secured to the other hanger 18 at the other side of the pulley 37, 50 so that when the operating cord 22 is pulled in one direction it will serve to move the hangers 18 apart, while the operating cord 22 may be pulled in the other direction to draw the hangers 18 in the direction of 55 each other.

The hangers 18 will be engaged by the hangers 18 and will be moved accordingly. The terminals 29 of the operating cord 22 extend over pulleys 38 mounted in a bracket 60 39 which is supported by a bolt 40, the said bolt 40 extending through a block 41 disposed over the bracket 39 and through a U-shaped member 42 which is disposed through an opening 43 in the bottom of the guide 65 10 and which has one of its arms disposed

above the bottom of the guide and its other arm disposed below the bottom of the guide.

What I claim is:

1. In a curtain pole, a casing having an opening in its top and a slot in its bottom, 70 a guide in the casing having an opening in its top and a slot in its bottom, a support having an opening, a pin disposed through the openings for holding the guide and the casing in position relatively to each other 75 and to the support, a hanger extending through the slots, and roller means mounted on the hanger and engaging the guide at the sides of the slot therein.

2. In a curtain pole, a guide having a 80 slot in its bottom and with its top bent upwardly to form a U-shaped portion, a casing in which the guide is disposed and provided with an inverted U-shaped portion at its top in which the U-shaped portion of 85 the guide is disposed, a casing having a slot in its bottom, an inverted U-shaped support disposed with its arms at the sides of the U-shaped portion of the casing, registering orifices in the said U-shaped portions, a pin 90 extending through the orifices, a hanger extending through the slots, and roller means mounted on the hanger and engaging the guide at the sides of the slot therein.

3. In a curtain pole, a hanger having an 95 eye and guides, a cord extending through the eye and a plate slideable in the guides and having a wedge for pressing the cord at the eye for locking purposes.

4. In a curtain pole, a hanger having 100 eyes spaced apart and guides, a cord extending through the eyes, and a plate slideable in the guides and provided with a wedge engaging the cord between the eyes for pressing the cord at the eyes for locking 105 purposes.

5. In a curtain pole, a hanger having eyes spaced apart, a cord extending through the eyes, a plate slideable in the guides and provided with a wedge engaging the cord between the eyes for pressing the cord at the 110 eyes for locking purposes, and means for locking the plate relatively to the hanger.

6. In a curtain pole, a hanger having an eye and guides, a cord extending through 115 the eye, a plate slideable in the guides and provided with means for locking the cord at the eye.

7. In a curtain pole, a hanger having two eyes spaced apart and guides, a cord extending through the eyes, a plate slideable in the guides and having a wedge disposed under the cord between the eyes there being an opening in the hanger, and a spring tongue extending from the plate engaging the 125 hanger at the opening for locking purposes.

8. In a curtain pole, a hanger having two eyes spaced apart and guides, a cord extending through the eyes, a plate slideable 130

in the guides and having a wedge disposed under the cord between the eyes there being an opening in the hanger, a spring tongue extending from the plate engaging the hanger at the opening for locking purposes, there being registering openings in the bottom of the hanger and the plate to which a curtain pin may be attached.

9. In a curtain pole, a hanger having an eye and guides, a cord extending through the eye, a plate slideable in the guides and provided with means for locking the cord at the eye, there being registering openings in the bottom of the hanger and the plate to which a pin may be attached.

10. In a curtain pole, a guide having a slot in its bottom, a hanger disposed in the slot, rollers rotatably mounted at the sides of the hanger which engage the guides at

the sides of the slot, the hanger having two 20 eyes spaced apart and guides, a cord extending through the eyes, and a plate slideable in the guides and provided with a wedge engaging the cord between the eyes for pressing the cord at the eyes for lock- 25 ing purposes.

11. In a curtain pole, a guide having a slot, a hanger disposed in the slot and provided with a bearing, a stud journaled in the bearing, rollers mounted on the stud at 30 the sides of the hanger which engage the guides at the sides of the slot, the hanger having an eye, and guides, a cord extending through the eye, and a plate slideable in the guides and provided with a wedge for press- 35 ing the cord at the eye for locking purposes.

FRANK JOSEPH BISCHOF.
